OSCILLOSCOPE CAMERA HOOD

Billy H. Vinson, San Diego, Calif., assignor to
Integrated Controls, Inc.

Filed Sept. 14, 1970, Ser. No. 24,972

Term of patent 14 years

Int. Cl. D16—05

U.S. Cl. D61—1

FIG. 1.

FIG. 2.

FIG. 3.

FIG. 4.

FIG. 5.

FIG. 1 is a perspective view of an oscilloscope camera hood showing my new design;

FIG. 2 is a rear elevational view thereof;

FIG. 3 is a front elevational view thereof;

FIG. 4 is a left side elevational view thereof; and

FIG. 5 is a top plan view thereof.

I claim:

The ornamental design for an oscilloscope camera hood, substantially as shown.
